United States Patent Office.

FREDERICK W. JUDD, OF NEW BRITAIN, ASSIGNOR TO HIMSELF AND
EDWARD M. JUDD, OF NEW HAVEN, CONNECTICUT.

Letters Patent No. 97,929, dated December 14, 1869; antedated December 9, 1869.

IMPROVED CARPET-STRETCHER AND TACK-HOLDER.

The Schedule referred to in these Letters Patent and making part of the same.

To all whom it may concern:

Be it known that I, FREDERICK W. JUDD, of New Britain, in the county of Hartford, and State of Connecticut, have invented and made a new and useful Combined Carpet-Stretcher and Tack-Holder; and I do hereby declare the following to be a full, clear, and exact description of the said invention, reference being had to the annexed drawing, making part of this specification, wherein—

Figure 1 is a plan of said implement, and
Figure 2 is a side view of the same.

Similar letters denote the same parts.

A carpet-stretcher is a great convenience in putting down carpets, but frequently the carpet is allowed to draw back while the tack is being applied. This often results from having to move the carpet-stretcher out of the way, so as to insert a tack in the part that had been stretched.

My invention consists in a spring, with a slot at the end for suspending a tack, in combination with a carpet-stretcher, so that the tack can be driven into the carpet, the slotted spring yielding as the tack is struck by the hammer.

In the drawing—

a represents a portion of a handle, of any desired length or size.

b is the carpet-stretcher, with teeth in the end.
c is a notch, near the central portion of the carpet-stretcher.

e is a spring, attached at *i*, and slotted at the end *o*, so as to suspend a tack, *l*, by the head, over the notch *c*, so that the carpet-stretcher can be used without the point of the tack necessarily coming into contact with the carpet.

When the tack is to be driven, a blow from a hand-hammer causes the tack to penetrate sufficiently to hold in the floor, the spring *e* yielding.

The stretcher is then to be drawn back, and the driving of the tack completed.

I do not claim a spring-clamp to hold the latch, combined with a carpet-stretcher.

What I claim, and desire to secure by Letters Patent, is—

The spring *e*, formed with the slot *o*, for suspending the tack, in combination with the carpet-stretcher *b*, as and for the purposes specified.

In witness whereof, I have hereunto set my signature, this 10th day of May, 1869.

FRED. W. JUDD.
